P. A. FRANK

SAFETY RAZOR AND SHARPENER

Filed Nov. 2, 1923

10 Inventor
Paul A. Frank
By Willard D. Eakin
Atty.

UNITED STATES PATENT OFFICE.

PAUL A. FRANK, OF AKRON, OHIO.

SAFETY RAZOR AND SHARPENER.

Application filed November 2, 1923. Serial No. 672,369.

To all whom it may concern:

Be it known that I, PAUL A. FRANK, a citizen of the United States, residing at Akron, in the county of Summit and State 5 of Ohio, have invented certain new and useful Safety Razors and Sharpeners, of which the following is a specification.

This invention relates to safety razors and devices for sharpening the same.

10 My chief objects are to provide an improved safety razor and an improved sharpener therefor wherein the blade may be quickly, easily, and evenly sharpened without removing it from its holder and 15 without requiring so high a degree of skill as is required in the case of razors and strops such as heretofore have been known. More specific objects are to provide an improved razor sharpener of the rotating- 20 cylinder type adapted to be used upon a blade while the latter remains pivoted in its holder, to be quickly and easily applied to and removed from the razor, and to be easily and accurately held in operative relation to 25 the latter. A further object is simple and inexpensive construction.

Of the accompanying drawings:

Fig. 1 is an end elevation of my sharpening device in its preferred form, in open position to receive the razor, the supporting ring shown in Fig. 2 being omitted.

Fig. 2 is a side elevation, as viewed from the left of Fig. 1, of the sharpener, a part being broken away and shown in section.

35 Fig. 3 is an end elevation of the sharpener and my improved razor therein, in operative relation.

Fig. 4 is an end elevation of the sharpener as viewed from the left of Fig. 2, parts being 40 broken away to show the blade-oscillating mechanism.

Fig. 5 is an elevation of the razor with its blade secured in position for use.

Fig. 6 is an end view of the razor.

45 Fig. 7 is a plan view of the blade.

Fig. 8 is a perspective view of a blade oscillating member.

Referring to the drawings, 10 is a razor handle screwed into a blade-holding head 50 11, the latter preferably comprising a stamped piece of sheet metal having parallel, journal-ear portions 12, 12 bent away from the handle 10 and a blade-supporting, bracket portion 13 projecting laterally of the handle 10, said bracket portion being formed with the usual guard

teeth 14, 14 adapted to underlie the cutting edge of the blade, and with end-guard teeth 15, 15 between which the cutting margin of the blade may seat. 16 is the 60 blade, which is pivoted between the ears 12 of the head 11, being preferably formed, as here shown, with a clamping portion 17 at its back, of less length than the full length of the blade, and with perforations 65 18, 18 (Fig. 7) adjacent said clamping portion, the blade thus being adapted to be held by a broad spring clamp 19 pivoted on a shaft 20 mounted in the ears 12, said clamp being dimpled, as shown at 21, 21 70 (Fig. 6) to provide detents adapted to enter the perforations 18 of the blade to hold the latter in the spring clamp. 22 are spacing collars rotatably mounted on the shaft 20 between the spring clamp 19 and the respective ears 12, said collars being adapted to be clamped between parts of the sharpening device hereinafter described, to hold the razor in operative relation to the latter 75 while permitting the blade to be oscillated. 23 are blade clamping slides mounted in suitably apertured ears 24, 24 and 25, 25 stamped and bent up from the bracket portion 13 of the head 11, said slides being formed with respective hooked outer end 80 portions 23^a, 23^a adapted to engage the end margins of the blade to hold the latter in operative relation to the guard teeth 14, 15, and with bent inner end portions 23^b, 23^b 85 projecting through the opening in the head 90 11 formed by the stamping and bending up of the ears 24, the said inner end portions, 23^b, being adapted to be engaged by the fingers to draw the slides together into blade-holding position or to move them 95 apart to release the blade. The slides 23 may be formed with dimple detents, as indicated at 26, 26, coacting under spring action of said slides, with complementary dimples (now shown) stamped in the face 100 of the bracket member 13, to secure the slides in blade-holding position.

The sharpening device comprises a pair of journal-frame members 27, 28, which 105 may be formed of stamped and bent sheet metal, said frame members being formed with parallel, curved, hinge arms 27^a, 27^a, 28^a, 28^a at their ends, said arms being hinged together in pairs at their outer ends by a pin or shaft 29 common to the four 110 arms and provided with a spacing sleeve 30 between the two pairs of arms, as shown

clearly in Fig. 2. 31 is a ring secured to the middle of said spacing sleeve, for supporting the device, either when in use or not, while permitting the frame members 5 to be swung toward or away from each other to clamp the device upon or remove it from the razor, said frame members being formed with notched clamping jaws 27^b, 27^b, 28^b, 28^b adapted to be closed upon the 10 collars 22 of the razor, to hold the latter accurately in the sharpening device, as shown in Fig. 3, while permitting its blade to be oscillated.

15 Abrading cylinders 32, 33, adapted to receive the blade 16 in a sharpening action, are secured on respective shafts 34, 35, journaled in the frame members 27, 28 at such positions that the cylinders will be spaced apart when the frame members are 20 in clamping position, and secured on said shafts at adjacent ends of said cylinders are respective spur gears 36, 37 adapted to mesh with each other when the frame members are moved together into clamping 25 position, and the shaft 35 is provided at its front end, outside of the frame member 28, with a hand crank 38, for turning the cylinders.

30 For oscillating the blade so as yieldingly to hold it for a time against one and then against the other of the rotating abrading cylinders, to abrade the respective faces of its cutting edge, a cam-actuated lever 39, formed at one end with a pair of laterally 35 projecting spring fingers 39^a, 39^a adapted to embrace the blade, is pivoted, near its middle, at 39^b (Fig. 4), upon an ear 28^c formed upon the rear arm of the frame member 28, and is formed at its other end with a pair of 40 cam-follower fingers 39^c, 39^c straddling a reciprocator cam 40 secured to a large spur gear 41 journaled upon the shaft 29 at the rear end of the spacing sleeve 30 and meshed with a small spur gear 42 secured 45 upon the shaft 34.

50 The number of teeth on the gear 41 is preferably almost but not exactly a multiple of the number of teeth on the gear 42, so that the blade in its successive oscillating movements toward each cylinder will contact the cylinder at a slightly different position, so as to avoid excessive localized 55 wear of the cylinder at any part of its circumference.

55 While the abrading cylinders here shown are of a type commonly used for stropping, I do not wholly limit my invention thereto, as other types or abrading cylinders obviously may be used.

60 In the operation of sharpening the razor, the blade is released by forcing the slides 23 apart and is turned about its pivot substantially into alignment with the handle 65 10. The frame members of the sharpening device being opened out as shown in Fig.

1, said device is introduced to the razor so that its cylinders straddle the blade. The frame members are then closed toward each other and by the hand are held clamped upon the sleeves 22 of the razor, and the hand crank 38 is turned clock-wise as viewed in Fig. 3, driving the abrading cylinders and, through the train of gearing above described, driving the cam 40, which, through the lever 39 and the latter's spring fingers 39^a, yieldingly holds the blade for an appreciable time against one of the rotating cylinders and then the other, in succession.

15 The blade is thus sharpened without such unevenness of effect as frequently occurs in self-sharpening razors of the reciprocating-strop type; without requiring much skill or care on the part of the operator, the element of skill being almost completely eliminated; and without removing the blade 20 from its holder.

25 To facilitate the holding and steadyng of the device in use it may be pulled by the hand gripping the frame, the latter being suspended by the ring 31, or it may be 30 simply held in one hand without such suspension.

35 The ears 12 of the blade-holding head, abutting the respective spacing collars 22, provide means permanently mounted and consequently always present upon the shaft 20, for positioning the latter longitudinally with relation to the frame members as the latter are closed about the end portions of the shaft, so that the mounting of the sharpener requires simply the closing of the frame members upon the razor, avoiding dangerous handling or manipulating of the blade and at the same time providing the necessary accuracy of position.

40 Modifications may be resorted to within the scope of my invention, and I do not wholly limit my claims to the specific construction shown.

45 I claim:

1. A sharpener comprising a frame structure adapted to be clamped on a safety razor, a pair of spaced apart abrading cylinders mounted on said frame structure and adapted freely to receive the razor blade between them, means for driving said cylinders, and means for so oscillating said blade as to hold it against one and then the other of said cylinders.

2. A sharpener comprising a frame adapted to be clamped upon a safety razor, a pair of abrading cylinders in said frame, means for driving the cylinders, a blade oscillating lever having a pair of fingers adapted to straddle the blade, and a cam driven by said cylinder-driving means for actuating said lever.

3. A sharpener comprising a frame adapted to be clamped upon a safety razor, a pair of abrading cylinders in said frame, means

for driving said cylinders, and blade oscillating means actuated by said driving means and including a pair of spring fingers adapted to straddle the blade to hold it yielding-
5 ly against one and then the other of said cylinders.

4. A sharpener comprising two frame members adapted to be clamped upon a safety razor, a pair of abrading cylinders
10 mounted in said frame members respectively, means for driving said cylinders, means actuated by said driving means for holding the razor blade against one and then the other of said cylinders, and means by which
15 the sharpener may be suspended from a support to facilitate holding it against the force of the cylinder driving means.
5. The combination of a clamp adapted to grip the base of a safety razor blade, a
20 shaft constituting a mounting for said clamp and having end portions projecting therefrom, a pair of frame members adapted to be closed together about the projecting end portions of the shaft while accom-
25 modating the blade between them, means permanently mounted upon the end portions of the shaft for positioning said shaft with relation to said frame members as the latter are so closed together, said means and
30 said frame members being adapted to be associated by a simple closing movement of the latter, abrading cylinders journaled in said frame members respectively and adapted to abrade the opposite sides of said
35 blade, and means for driving said cylinders.

6. A blade sharpener comprising a pair of relatively movable frame members hav-

ing respective clamping portions adapted to embrace a part of the mounting of a pivoted 40 blade, a pair of abrading cylinders mounted respectively on said frame members, in position to straddle said blade, driving means for said cylinders, a blade oscillating lever pivoted on one of said frame members and formed with a pair of fingers adapted freely to receive said blade between them, and a cam, driven by said cylinder- 45 driving means, for actuating said blade-oscillating lever.

7. A blade sharpener comprising a hinged pair of frame members having clamping portions adapted to be closed together upon a part of the mounting of a pivoted blade, a pair of abrading cylinders mounted 50 respectively upon said frame members, a pair of gears concentric with and compelled to rotate with said cylinders, said gears being adapted to mesh and unmesh as said frame members are swung toward and from each 55 other, a reciprocator cam journaled concentrically with relation to the hinge of said frame members, a two-armed, blade-oscillating lever pivoted on one of said frame members and formed on one arm with a pair 60 of fingers adapted freely to receive said blade between them, the other arm of said lever being formed with a cam-follower portion associated with said cam, driving means operatively connecting one of said gears 65 with said cam, and means by which one of said cylinders may be rotated.

In witness whereof I have hereunto set my hand this 30th day of October 1923.

PAUL A. FRANK.
